(57) **CLAIM**

The ornamental design for a substrate for manufacturing
cutting elements, as shown and described.

DESCRIPTION

FIG. 1 is a perspective view of a substrate showing my new
design;

FIG. 2 is a top view of the substrate of FIG. 1;

FIG. 3 is a side view of the substrate of FIG. 1; and,

FIG. 4 is a bottom view of the substrate of FIG. 1.
